ELECTRICAL RELAY

Filed Dec. 24, 1930

UNITED STATES PATENT OFFICE

NOBLE C. SHAW, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL RELAY

Application filed December 24, 1930. Serial No. 504,459.

My invention relates to electrical relays.

I will describe one form of electrical relay embodying my invention, and will then point out the novel features thereof in claims.

In the accompanying drawings, Fig. 1 is a vertical sectional view showing one form of relay embodying my invention. Fig. 2 is an isometric view of the contact member C forming a part of the relay shown in Fig. 1. Fig. 3 is a fragmentary bottom view of a portion of the relay shown in Fig. 1.

Similar reference characters refer to similar parts in all three views.

Referring first to Fig. 1, the reference character A designates the top plate of a relay. This top plate is made of some suitable insulating material, such as a phenol condensation product and carries an electromagnet B. The cores 1 of this electromagnet, only one of which is shown in the drawings, pass through the top plate A and terminate, on the other side of the top plate, in pole pieces 2. Secured to the pole pieces 2 by means of screws 3 is a bracket 4. An armature 5 of magnetizable material, such as soft iron, is pivotally supported on pivot pins 6 carried by bracket 4, and is arranged to be drawn upwardly toward the pole pieces 2 when magnet B is energized. Attached to the underside of armature 5 is a support 7 of suitable insulating material, such as a phenol condensation product, which support in turn, carries a flat contact finger 8. When magnet B is deenergized, armature 5 drops down under the influence of gravity, and finger 8 then engages a fixed back contact 9 which is fastened to top plate A by means of a binding post 10. When magnet B is energized, however, armature 5 is drawn upwardly into engagement with a core pin 11, as illustrated in the drawings, and contact finger 8 then engages a fixed front contact member C embodying my invention, which contact member I will now describe.

Referring now also to Figs. 2 and 3, the contact member C comprises a holder 12 of suitable electro-conductive material, such as brass, having a substantially horizontal upper portion 12^a and an integral depending portion 12^b. The upper portion 12^a fits

snugly between parallel ribs 15 formed on the underside of the top plate A, as best seen in Fig. 3, and is provided with a hole 12^c which receives the shank 13 of a bolt 14^a forming part of a terminal post 14 mounted on top plate A. It will be apparent, therefore, that the bolt 14^a securely fastens the holder to the top plate, while the ribs 15 on the underside of the top plate prevent the holder from turning. The depending portion 12^b of the holder 12, as here shown, is inclined at an angle of approximately 120° with the upper portion 12^a, and is provided at its lower end with two spaced parallel plates 12^d and 12^e. These plates are joined at one edge by an integral web 12^f, and are provided with registering openings 12^g and 12^h, respectively, as illustrated in Fig. 1. A flat contact block 17 preferably of graphite, is interposed between the plates 12^d and 12^e of holder 12. This contact block, as here shown, is rectangular in shape. A screw 18 passes through the openings 12^g and 12^h in the plates of holder 12 and also through a hole 17^a in block 17. The holes 12^g and 12^h as well as the hole 17^a are preferably of such size as to make a snug fit with the screw 18. A nut 19 is screwed onto the threaded end of screw 18, and the screw and nut are locked in place by lock washers 20 and 21, respectively.

In order to prevent the contact block 17 from turning in the holder 12 in the event that the screw 18 should become loosened for any reason, it is desirable that the web 12^f should engage the side of the contact block throughout the vertical length of the web. This would be difficult to accomplish if the web were made flat, because in manufacturing a holder of the type described it is desirable to provide a rounded corner having a radius approximately equal to the thickness of the web at those portions of the web where the web joins each of the plates 12^d and 12^e to prevent the metal from cracking during bending, and these rounded corners prevent the web from engaging the edge of the contact block except at the sharp corner of the block. I therefore provide the web with a centrally disposed longitudinally extending

reentrant portion 12^j which is of such a depth that when the contact block is in place this reentrant portion engages, throughout its entire length, the adjacent edge of the contact block. It will be apparent, therefore, that with the web constructed in this manner, the block will be securely held in its proper aligned position in the holder even though the nut 19 should become loosened sufficiently so that the contact block is no longer securely clamped between the plates. The reentrant portion 12^j also serves to add a degree of flexibility to the web which permits the parallel plates 12^a and 12^e to be drawn together to engage the contact block when the nut is tightened.

It will be seen from an inspection of Fig. 1, that the holder extends from the top plate at such an angle that the lower corner 17^b of the contact block makes contact with the contacting portion of the finger 8 when the armature 5 is drawn upwardly due to magnet B becoming energized. It will also be seen that by reversing the contact block in the holder, so that the upper side of the block as shown in Fig. 1 becomes the lower side, the corner 17^c may be brought into substantially the same position in which the corner 17^b is shown in the drawings, and this corner will then be in the proper position to make contact with the contacting portion of the finger 8 when magnet B is energized. The dimensions of the contact block 17 are such that wear on either corner will not effect the other corner, and it follows that in a relay provided with a holder embodying my invention, the useful life of the contact block will be twice that of the contact block ordinarily employed in relays of the type described.

One advantage of a contact member embodying my invention is that it is simple in design and therefore inexpensive to manufacture.

Another advantage of a contact member embodying my invention is that improper alignment of the contact block is positively prevented. This is important because relays of the type described are frequently employed in railway signaling systems where misalignment of a contact might result in a dangerous signal indication.

Although I have herein shown and described only one form of electrical relay embodying my invention, it is understood that various changes and modifications may be made therein within the scope of the appended claims without departing from the spirit and scope of my invention.

Having thus described my invention, what I claim is:

1. In combination, a contact holder having spaced parallel plates joined by a web, and a contact block clamped between said plates, said web being provided with a reentrant portion

which engages said block to maintain said block in the proper position in said holder.

2. In combination, a contact holder having spaced parallel plates joined at one edge by an integral web which is crimped to form a reentrant portion, and a contact block clamped between said plates in such manner that said reentrant portion engages one edge of said block and maintains said block in the proper position in said holder.

3. In combination, a contact holder having spaced parallel plates provided with registering openings, said plates being joined by an integral web provided with a reentrant portion, a screw passing through said openings, and a flat substantially rectangular contact block clamped between said plates by means of said screw in such manner that said reentrant portion engages one edge of said block and holds said block in the proper position between said plates.

4. In combination, an electrical contact structure for cooperation with a movable contact finger, said structure comprising a contact holder having a depending portion provided at its lower end with two parallel plates connected by an integral web, and a flat contact block clamped between said plates, said web being crimped to form a reentrant portion which engages one side of said block for maintaining said block in proper alignment with respect to the contacting surface of said movable contact finger.

5. An electrical contact structure for a relay comprising a contact holder having a depending portion provided at its lower end with two parallel plates formed with registering openings, a screw extending through said openings, a flat substantially rectangular contact block having a hole to accommodate said screw with a tight fit, said contact block being clamped between said plates by said screw, and an integral relatively flexible web connecting said plates, said web being provided with a reentrant portion which engages one edge of said block for maintaining said block in a fixed position between said plates even though said screw becomes loosened.

6. An electrical contact structure comprising a contact holder having a first flat portion provided with a hole adapted to receive means for featuring the contact structure to an electrical device, a depending portion integral with said first portion and provided at its lower end with two spaced parallel plates having registering openings, said plates being joined at one edge by an integral web which is crimped to form a reentrant portion, a flat substantially rectangular contact block located between said plates and provided with a hole adapted to register with the openings in said plates, a screw extending through all of said openings, and a nut on said screw for clamping said block between said plates, said reentrant portion being so designed that it en-

gages one edge of said contact block and prevents said block from turning about said screw between said plates.

7. The combination with a relay top plate 5 and a contact finger movable in a path which is fixed with respect to said top plate, of a contact structure comprising a contact holder attached to said top plate and having a depending portion provided at its lower end with two 10 spaced parallel plates joined by an integral web formed with a reentrant portion, said plates being provided with registering openings, a screw passing through said openings, and a flat substantially rectangular block 15 clamped between said plates by means of said screw in such manner that said reentrant portion engages one edge of said block and prevents said block from turning between said plates, said holder being so disposed with respect to said finger that one lower edge of 20 said block is normally in the proper position to cooperate with the contacting portion of said finger but that by reversing said block in said holder the opposite lower edge of said block may be brought into the proper position 25 to cooperate with the contacting portion of said finger, whereby the life of said block is doubled.

In testimony whereof I affix my signature.
